UNITED STATES PATENT OFFICE

THOMAS GONGORA, JR., OF ST LOUIS, MISSOURI

RADIO RECEIVING SYSTEM

Application filed February 10, 1927. Serial No. 167,212.

This invention relates to radio-receiving systems, and the object thereof is to provide a system of that character that will possess the combined advantages of great sensitivity, 5 selectivity, volume, ease of control, tone quality, simplicity, and reduction or suppression of static or strays, and the like. Systems have hitherto been provided that are highly sensitive, but they have been extremely 10 difficult to control. One such system that may be mentioned for the purpose of illustration is the homodyne system of reception, in which the results are obtained by impressing the incoming carrier waves on the grid circuit of a thermionic valve or tri-electrode vacuum tube normally in a state of oscillation, the system being adjusted so that the local oscillations suppress the carrier wave 15 by the principle of zero-beat reception, as will be understood by those skilled in the art. It is, however, extremely difficult to control and to adjust the local oscillations 20 to the proper frequency and phase relation to the incoming waves, there being a tendency 25 to instability and distortion of signals and the production of squeals, beat notes, and the like.

Briefly described, the present invention 30 purposes broadly to impress the incoming waves on the plate or output circuit of a normally oscillating receiving system, instead of on the grid or controlling circuit, so that the aforementioned condition of instability is obviated. The present invention is applicable 35 to homodyne, heterodyne, and other circuits, and is not limited in its use to the two circuits which have been selected for the purpose only of illustrating the invention.

In the accompanying drawing forming 40 part of this specification, in which like numbers of reference denote like parts wherever they occur, the Figures 1 and 2 are diagrams which illustrate two embodiments of this invention.

The oscillating circuits of Figures 1 and 50 2 comprise a plate 1, grid 2, and filament 3 of a thermionic valve or vacuum tube normally in a state of oscillation, the grid circuit 4 including the usual grid condenser 5, grid resistance 6, tuning condenser 7, and

feed back or coupling coil 8, and the plate circuit 9, including the coupling coil 10, source of plate current supply or "B" battery 11, radio-frequency choke coil 12, and telephone receiver 13. The filament 3 is supplied with current from any suitable source, such as an "A" battery 14, and the filament current may be regulated by the rheostat 15 in the filament circuit 16.

In Figure 1, a wave-collecting circuit 17, including aerial 18, ground 19, and adjustable inductance 20, is connected to the plate circuit 9 through a lead 21. In Figure 2, the wave-collecting circuit 22 comprises antenna 18, ground 19, adjustable inductances 23 and 24, and coupling coils 25 and 26, coil 25 being included in the plate circuit 9 and coil 26 in the aerial circuit 22. Coils 25 and 26 and circuits 9 and 22 are connected by a lead 27. A condenser 28 in Figure 2 prevents shorting of the battery 11.

The incoming modulated carrier waves are collected by the circuits 17 and 22 and pass into the plate circuit 9, being prevented from passing into the grid circuit 4 by the radio-frequency-choke coil 12. The separation of the coils 8 and 10 governs the coupling of the grid and plate circuits 4 and 9, respectively, and by adjusting the coupling to the best point the selectivity is increased or decreased, as desired. It can, also, be fixed at an optimum value. The frequency of the circuit 4 is adjusted by the variable condenser 7 to the frequency of the incoming waves, and the phase relation between the incoming waves and the oscillations of the plate circuit 9 is determined by adjusting the inductance 20 of aerial 17, and in the case of aerial 22, by adjusting the variable inductances 23 and 24 and the coupling coils 25 and 26. The adjustments of these coils and inductances, also assist in tuning the aerials, as will be understood by those skilled in the art.

As is well known in the radio science, the incoming modulated carrier wave that is collected by the aerial is composed of a frequency f which is called the carrier wave, and modulation frequencies f^1, f^2, f^3 , etc. In order to simplify matters, let it be considered that these modulation frequencies, which are

extremely complex, all combine and produce a resultant modulation current FM. In that case, there is in the aerial and ground system two currents: a radio-frequency current or carrier wave f and impressed on this current f there is the modulating audio-frequency current FM. The combination of currents f and FM produce a modulated carrier wave whose value may be expressed by the algebraic sum of f and FM, or by the quantity $f+FM$. Now, if this modulated carrier wave is impressed upon the plate circuit 9 in such a way that the radio frequency current in the circuit 9 is of the same frequency as and in opposite phase, or at a phase angle of 180° , to the modulated radio frequency striking the aerial and ground system, a condition of "zero beat" is obtained and the carrier wave is destroyed, leaving only in the plate circuit of the tube the modulating current FM, which was impressed at the transmitting station upon the carrier wave. This audio-frequency current FM is heard in the phones 13.

The choke coil 12 is used in order to prevent the radio-frequency-carrier wave f from getting into the grid circuit 4 through the filament connection. If this frequency were admitted into the grid circuit, it would produce low frequency beats which would make reception very difficult if not impossible.

A very large resistance 29, about twenty megohms, the magnitude of which is determined by the constants of the tube and within certain limits, also, by the frequency of the oscillating current in the tube circuit, is used to provide a leakage path between the plate and the grid, so as to highly resist the passage of the carrier waves and to make the oscillation more stable. It, also, serves to impress the audio-frequency currents, released in the plate circuit 9, upon the grid 2, so that audio amplification is obtained thereby.

As is well known in the art, this system of reception is called the zero-beat, or homodyne, system of reception and is used for illustrative purposes only, and not in a limiting sense. Any other suitable oscillating circuit may be used, such, for instance, as the heterodyne for telegraphic purposes, when the beat current obtained may be of any value other than zero. While the illustrated embodiments employ an antenna and ground connection, other wave-collecting means may be employed and coupled to the plate or output circuit of an oscillating system, such, for instance, as a loop, or a collector connected to the ground alone, or to the antenna alone, or an aerial and counterpoise collector. Also, the collector need not be directly coupled or directly connected to the output circuit 9, but the connection or coupling may be indirect through the intermediary of amplifiers or other devices or circuits. This invention

can, also, be incorporated in a wave meter, transmitting system, or other devices.

The sensitivity and selectivity of this system is believed to be very much greater than that of any other system known at present. The volume is the same as that obtained from a regenerative circuit at best adjustment. The tone quality is natural, provided it has not been sacrificed for the sake of selectivity, when adjusting the oscillating circuit. The signal is clear from all distortion, squeals, beat notes, and the like, and always at highest volume for each wave length tuned. It is easy to tune without many adjustments, and can be designed so that it may be operated from a single dial. Since the aerial and ground is connected to the plate circuit and not to the grid circuit, the static, strays, and the like are not amplified as in other circuits or are not received at all, since the circuit is responsive preferentially to a modulated carrier wave, which is reacted upon by the local oscillator. A connection to the ground can be used only and no difference in signal strength has been detected, provided the ground system is of the right inductance and capacity. When using an aerial and a ground or a ground connection only, the inductance or capacity or both are varied for the best operating point and there is no need of retuning for each wave length that is received, provided the range is within the range of frequencies produced by the local oscillator.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. A radio-receiving system for reproducing the modulating side bands of a modulated carrier wave that comprises a space discharge device and input and output circuits therefor having a common cathode, means for tuning the system to the frequency of the incoming wave, wave-collecting means coupled to the output circuit, and a filter offering high impedance to the frequency of the carrier wave but resonant to the modulating frequencies of the carrier wave, said filter being located in the output circuit connection to the common cathode to exclude the carrier wave from the input circuit.

2. Means for reproducing the modulating side bands of a modulated carrier wave comprising a space discharge device and input and output circuits having a common cathode and coupled so as to produce oscillations therein, means for tuning the system to generate a frequency equal to that of the carrier wave, means for superimposing the modulated carrier wave upon the output circuit,

signal means in the output circuit, the portion of said output circuit between the signal means and the common cathode having an impedance that represses the carrier wave but not its modulating frequencies.

5 3. Means for reproducing the modulating side bands of a modulated carrier wave, comprising a space discharge device having a grid circuit and an anode circuit connected through a common cathode, both circuits being coupled so as to produce oscillations, means for tuning the system to generate a frequency equal to that of the carrier wave, means for superimposing the modulated carrier wave upon the anode circuit, a signal-indicating device in the anode circuit, and a filter located in the anode circuit between the signal-indicating device and the common cathode and offering high impedance to the frequency of the carrier wave but resonant to the modulating frequencies of the carrier wave.

4. A receiving system for reproducing the modulating frequencies of a modulated carrier wave, consisting of a space discharge device having a controlling circuit and an anode circuit connected through a common cathode, both circuits being inductively coupled so as to normally generate oscillations, means for tuning the system to generate a frequency equal to that of the modulated carrier wave, signal collecting means included in the anode circuit, and a filter in series in the anode circuit to exclude the modulated carrier wave from entering the controlling circuit, by way of the connections to the common cathode, but offering low impedance to the modulating frequencies of the carrier wave.

20 40 In testimony whereof I hereunto affix my signature.
